US00D953445S

(12) United States Design Patent (10) Patent No.: US D953,445 S
Chia et al. (45) Date of Patent: * May 31, 2022

(54) CAP OF A TOY DART

(71) Applicant: Easebon Services Limited, Kwun Tong (HK)

(72) Inventors: Francis See Chong Chia, Kowloon (HK); Xubin Xia, Guangdong (CN)

(73) Assignee: EASEBON SERVICES LIMITED, Kwun Tong (HK)

() Term: 15 Years

(21) Appl. No.: 29/761,117

(22) Filed: Dec. 7, 2020

(51) LOC (13) Cl. 21-01

(52) U.S. Cl.

USPC D21/570; D21/301; D21/387

(58) Field of Classification Search

USPC D21/567, 570, 573, 572, 574, 575; D22/103–105, 108, 116

CPC .. F42B 6/00; F42B 6/003; F42B 30/02; F41B 11/89; F41B 7/08; F41B 9/0018

(57) CLAIM

The ornamental design for a cap of a toy dart, as shown and described.

DESCRIPTION

FIG. 1 is a first perspective view of a new design for a cap of a toy dart.

FIG. 2 is a second perspective view thereof;

FIG. 3 is a left side view thereof;

FIG. 4 is a right side view thereof;

FIG. 5 is a front view thereof;

FIG. 6 is a back view thereof;

FIG. 7 is a top view thereof; and,

FIG. 8 is a bottom view thereof.

The dart body is shown in broken lines for illustrative purposes only and forms no part of the claimed design.

1 Claim, 4 Drawing Sheets
